UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 12,821, dated March 21, 1882.

Application filed January 26, 1882. Term of patent 3½ years.

To all whom it may concern:

Be it known that I, ARTHUR L. HALLIDAY, of New York, in the county and State of New York, have invented a new and original Design for Carpets, of which the following is a specification.

This invention relates to a new and original design for carpets and similar fabrics; and it consists in the novel grouping and configuration of parts hereinafter more fully described.

The accompanying photograph illustrates a face view of a carpet having my new design.

The figure A represents a stripe ornamented with a series of rectangular figures placed side by side, and apparently resting upon a series of circular figures, below which runs a scalloped border, having one scallop below each of the circular figures.

The figure B is a band adjoining the stripe A, and contains a series of figures resembling hour-glasses laid sidewise, a large one alternating with a small one along the band.

The stripe C contains at its upper part an ornamental background, a, consisting of a series of lines or bars with rectangular knobs upon them at intervals. The lower part of the stripe C is composed of a series of pillars, b, supporting slender arches which cross each other.

The band D adjoins the stripe C and contains an ornamentation of a series of small crosses in a row, between which are dotted figures and other shorter crosses.

The stripe E contains a row of pointed figures with broken outlines, and having small figures in their centers.

The stripe F contains an ornamentation composed of the flower G, resembling a sun-flower; of the leaf H, one-half of which is seen in the photograph, resembling a palm-leaf; of the leaf I, composed of a center with leaves projecting around it; also, of the flower-like figure J, one-half of which is visible in the

photograph, and of the circular figure K, composed of a number of small rectangular figures placed together. The background of the stripe F is formed of small circles, rectangles, and crossing lines.

The band L is ornamented with a series of figures somewhat resembling hour-glasses, placed sidewise, below which runs a series of circular figures.

I claim—
